His Attorney.

UNITED STATES PATENT OFFICE.

GUY B. HUMES, OF CHICAGO, ILLINOIS.

ATTACHMENT FOR REED MUSICAL INSTRUMENTS.

1,409,180.

Specification of Letters Patent. Patented Mar. 14, 1922.

Application filed March 1, 1920. Serial No. 362,475.

To all whom it may concern:

Be it known that I, GUY B. HUMES, a citizen of the United States, and a resident of the city of Chicago, county of Cook, and 5 State of Illinois, have invented certain new and useful Improvements in Attachments for Reed Musical Instruments, of which the following is a specification.

My invention relates to attachments for 10 reed musical instruments, and has for its object the provision of means which, when used with reed musical instruments, will produce a discordant and inharmonious mingling of some of the tones issuing from 15 said instrument. Another object is the provision of a frame for retaining a vibrating element in position over the key of a reed musical instrument.

Other objects will appear hereinafter.

20 The invention consists in the combinations and arrangements of parts hereinafter described and claimed.

The invention will be best understood by 25 reference to the accompanying drawings forming a part of this specification, and in which,

Fig. 1, is a plan view of my invention,

Fig. 2, a plan view of the invention showing the clasp member inoperative,

30 Fig. 3, a fragmentary view showing a section of the invention as applied to a musical instrument,

Fig. 4, a sectional view taken on substantially line 4—4 of Fig. 3,

35 Fig. 5, a plan view of the vibrator used in the invention, and

Fig. 6, a side elevational view of the vibrator used in the invention.

The invention is designed for use with 40 reed musical instruments for the purpose of producing, when the instrument is played, what is popularly termed as a jazz effect, that is, the tones issuing from the instrument or from the key upon which the device 45 is positioned are broken up so as to result in inharmonious mingling of the tones which produces the harsh or gurgling sound.

The preferred form of construction comprises a frame 9 having a centrally located 50 orifice 10 therein. The frame portion proper comprises a circular portion having a flange 11, thereby providing a retaining portion for securing the ring 17 therein. This member 17 may be made of cork, card- 55 board, or other suitable material, upon one side of which is secured by means of glue

or other suitable material a vibrating disc 18, which may be formed from fish skin, oil paper, or the like. Projecting from one side of the member 9 is a suitable handle 60 12 to be used in placing the device in position. Projecting from the opposite side is a lug 13, in which engages the doubled-over portion of a strap 15 which is secured by any suitable means as by soldering at the points 65 where it contacts the periphery of a perforated cap 14. The extreme free end of the member 15 is bent at right angles and forms a clasp which engages in the slot 16 for the purpose of locking the member 14 70 in operative position. When the member 17 is positioned within the frame, the cap is moved to the position shown in Fig. 1, so as to retain the member 17 in position. The member 14 is shown perforated, in order to 75 allow a freer vibration of the member 18. The device is intended to be placed over a key or orifice 20 formed in a suitable reed musical instrument 21. The key stop 22, when the device is in operative position, 80 rests upon the member 14 and retains the device in operative position. Inasmuch as the member 15 is bent outwardly from the member 14, the member 22 is retained in spaced relation to the frame sufficiently to 85 permit escape of sound therefrom. Secured to the under surface of the frame is a felt or leather pad 23, which engages against the raised portion of the instrument at which the orifice 20 is formed so as to prevent 90 escape of air around the sides thereof.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of 100 the appended claims.

Having described my invention, what I claim as new and desire to secure by Letters Patent is:—

1. An attachment for reed musical instruments comprising a frame adapted for positioning over a key of the same; a vibrating element seated in said frame; and means for clasping said vibrating element in position on said frame, substantially as described. 105

2. An attachment for reed musical in- 110

struments comprising a frame adapted for positioning over a key of the same; a vibrating element positioned on said frame; and a perforated clasp member for retaining said vibrating element on said frame, substantially as described.

3. An attachment for reed musical instruments comprising a frame adapted for positioning over a key of the same, said frame having an opening therein; an annular member positioned on said frame, the opening of which registers with the opening in said frame; a vibrating element secured to said annular member; and means for retaining said annular member in position on said frame, substantially as described.

4. An attachment for reed musical instruments comprising a frame adapted for positioning over a key of the same, said frame having an opening therein; an annular member positioned on said frame registering with said opening in said frame;

a vibrating element secured to said annular member; and clasping means for retaining said annular member in position on said frame, substantially as described. 25

5. An attachment for reed musical instruments comprising a frame adapted for positioning over a key of the same, said frame having an opening therein; an annular member positioned on said frame registering with said opening in said frame; a vibrating element secured to said annular member; and a perforated clasp member 35 for retaining said annular member in position on said frame, substantially as described.

In testimony whereof I have signed my name to this specification in the presence of 40 two subscribing witnesses.

GUY B. HUMES.
